Carpets

NO. 11,501

Nov 11, 1879

UNITED STATES PATENT OFFICE.

ETIENNE GUIRAUD, OF NEW YORK, N. Y., ASSIGNOR TO THE BIGELOW CARPET COMPANY, OF CLINTON, MASS.

DESIGN FOR CARPET.

Specification forming part of Design No. **11,501**, dated November 11, 1879; application filed September 18, 1879.
[Term of patent 3½ years.]

To all whom it may concern:

Be it known that I, ETIENNE GUIRAUD, of New York, in the county and State of New York, have invented a new and original Design for a Carpet, of which the following is a specification.

The accompanying photographic illustration represents a face view of my newly-designed carpet.

This invention relates to a new and original design for carpets, oil-cloths, and similar fabrics, and for the border of the same.

It consists of the new ornamentation and grouping of the figures, hereinafter more fully described.

In the photographic illustration, the letter A represents the body of the carpet. B is the border of the same.

Upon the body A is represented a floral group, a. This group consists of a stem, l, which is divided into three principal branches, b, c, and d. Upon the branches b and c are represented several smaller flowers. The branch

d contains a large rose-like figure, e, and other larger flowers. From the stem l and branches b, c, and d project leaves of various shapes.

The group a is reproduced upon the background of the body A in the manner shown.

The border B is divided into stripes f, g, h, i, and j. The inner stripe, f, contains squares k at regular intervals. Upon the stripe g is represented a substantial reproduction of the branches c and d of the group a. The stripe h is arch-shaped opposite the stripe g, as shown.

I claim—

1. The design for a carpet, consisting of the groups a e d of floral ornaments, substantially as shown.

2. The design for a carpet, consisting of the group a, comprising stem l, branches b c d, and flower e, substantially as shown.

ETIENNE GUIRAUD.
